UNITED STATES PATENT OFFICE.

EDWIN H. MARBLE, OF WORCESTER, MASSACHUSETTS, ASSIGNOR TO CURTIS & MARBLE MACHINE COMPANY, OF WORCESTER, MASSACHUSETTS, A CORPORATION OF MASSACHUSETTS.

CLOTH-FOLDING MACHINE.

1,311,080.

Specification of Letters Patent. Patented July 22, 1919.

Application filed September 3, 1918. Serial No, 252,294.

To all whom it may concern:

Be it known that I, EDWIN H. MARBLE, a citizen of the United States, residing at Worcester, in the county of Worcester and 5 State of Massachusetts, have invented certain new and useful Improvements in Cloth-Folding Machines, of which the following is a specification.

This invention is applicable to cloth-folding machines of that class in which a backwardly and forwardly swinging pair of cloth-carrying folder-blades is employed for laying the cloth in oppositely directed folds upon a receiving table, and tucking the folded edge beneath projecting fold-retaining jaws, by the folder blade entering adjacently beneath the projecting edge of the jaw.

The prime object of my present invention is to provide a protector or warning guard, comprising an automatic means for preventing a person from inadvertently getting his hand or fingers pinched between the fold-retaining jaw and the approaching cloth-carrying folder-blade.

A further object is to provide a cloth-folding machine with a movable shield or safety device for guarding the junction of the jaw and folder-blades; and means for 30 operating said safety device actuated from the folder, operating shaft, or in connection with the folder actuating means.

Another object is to provide an oscillatable protective means or warning guard, 35 combined with and overlying the front fold-receiving jaw, and having an axis or rocking support parallel therewith; and means for automatically lifting or moving said guard, operative in conjunction with the operating means of the folder-blades or table action.

The nature and features of my invention are more clearly set forth and explained in the following description, with reference to 45 the accompanying illustrative drawings; the particular subject matter claimed being definitely expressed in the summary.

Of the drawings, Figure 1 represents a side elevation view of such parts of a cloth-folding machine as will illustrate the nature of my invention. Fig. 2 represents a plan view of a portion of the front end of a cloth-folding machine showing the top of the protector guard and adjacent parts. 50 Fig. 3 is a vertical section of the same at

line X X. Fig. 4 is an end view showing the guard elevated. Fig. 5 is a fragmentary side view showing a connecting joint for the guard-operating rod with the foot of the blade-supporting swing-bar. Fig. 6 is a 60 similar view illustrating position changes. Fig. 7 is a front detail view showing a portion at one end of the folder-blades and connections therefor, and Fig. 8 is a fragmentary view of the top end of the cam-levers and its actuating cam.

In its general construction and fold-forming operations the cloth-folding machine, with which my invention is designed to be incorporated, may be substantially such as 65 heretofore employed, or of any approved construction to which the present invention is applicable. A machine of such character, having my invention embodied therewith, is shown in outline in Fig. 1, and for a clearer 70 understanding of the same may be briefly 75 here described.

On the drawing, A denotes the frame; B the power shaft; C the operating-shaft having the cranks D and cams E, E¹ fixed thereon for rotative action; said shaft being rotated by pulleys and belt from the shaft B, or by other approved means.

F indicates the bed or table upon which the cloth is folded, in usual manner, by the 80 backwardly and forwardly moving folding-blades I which are pivotally mounted at their ends upon swinging supports G, and connected with the cranks D by a rod H at each side of the machine.

J indicates the front fold-retaining jaw, and J¹ the rear fold-retaining jaw, mounted 85 stationary upon the frame at the respective ends of the table; and L, L¹ denote the usual table-supporting mechanisms adapted for dropping and lifting the table for receiving 90 the folds from the blades I which are supported upon rods or bars G, to swing back and forth for carrying the web of cloth and tucking the alternate folds beneath the jaws. 100 M is the slasher guide-rod pivoted on the overhead bracket at P, and sliding through the head of the blade bar, as indicated on Figs. 1 and 7, for tipping the blades I forward or backward to their edgewise position 105 as they coact with the respective jaws J and J¹. As indicated in Fig. 1, the folder blades I are assumed to be moving toward the front jaw J.

R and R¹ indicate levers or swinging bars, 110

fulcrumed at their lower ends at f ; their upper ends being inwardly offset and provided with ears, or furcated, and each furnished with a roller r (see Figs. 1 and 8) 5 journalized therein, that contacts with its actuating cam E or E^1 , upon the operating shaft. The rod S connects the swing-bar R with the front table-operating mechanism L , and the rod T connects the swing-bar R^1 10 with the rear table-operating mechanism L^1 .

During the operation of folding cloth the folding-blades I enter beneath the jaws very close to the face thereof, when tucking the edge of the fold thereunder, the edge of the 15 table being for the instant depressed sufficient for its reception, as will be understood.

The forward swing of the folder-blades occurs from forty to sixty times per minute, 20 more or less, in the regular process of folding ordinary cloth fabrics.

The operator, standing at the front of the machine, at O , assists in guiding the cloth K by spreading or smoothing it out with his 25 hands, between the guide roll or bar at P and blades I , or between the blades and the front jaw J , as may seem necessary for keeping the fabric even and smooth. Through carelessness or inadvertence an operator, 30 inspector or overseer may, under ordinary conditions, unwittingly rest a hand upon the top of the jaw J , or fail to remove his hand from a position of danger as the folder-blades approach; consequently the fingers, if 35 extending beyond the edge of the jaw, may be hit or caught between the blades and jaw and thereby become severely pinched or injured. To obviate liability of such accidents I combine with the front jaw and fold-laying devices a movable guard or protective means arranged for automatically operating in co-active relation with the fold-forming mechanism, and preferably actuated by the same mechanism that operates 40 the swing of the folder-blades, said guard adapted for giving a warning action, or 45 forcing the removal of the hand from dangerous positions.

In the embodiment of my invention, I 50 range over the front fold-retaining jaw J , a movable shield or guard 2 , preferably extending longitudinally parallel therewith and formed to normally lie adjacent to the top surface of the jaw, at or near its working edge. Said guard is best supported by arms 3 fixed upon a rocker shaft or axis member 5 mounted in bearings 4 attached to the frame or body part of the jaw, and affording a hinging connection so that the 55 guard may be elevated or swing outward away from the top surface of the jaw, as indicated in Fig. 4, or closed down thereon, as indicated in Fig. 3.

An arm 6 is secured upon the shaft 5 , 60 and connected by a pivotally attached rod

7 with a suitable moving member of the folder mechanism, for imparting an elevative movement to the guard 2 synchronous with the approach of the folder-blades I toward the jaw J and before said blades 70 come into close conjunction therewith. In the present instance the rod 7 is connected with the swinging carrier G that supports the folding-blades I . The fulcrum block or member 8 at the foot of said carrier is provided 75 with a stud 9 fixed in, and projecting from said member and positioned eccentric to the fulcrum pivot 10 . The lower end of the guard-actuating connection rod 7 is provided with an elongated eye 12 80 in which said stud engages for operatively uniting the parts, but permitting a predetermined degree of lost motion between the limits of the eye, so that the protecting guard will be actuated only at a given interval of the folder-blade movement. Figs. 5 and 6 illustrate the relation 85 of the stud and eye at different positions in the swing of the folder-blade movement.

The operating cranks D and connections H and G are, in practice, arranged at each side of the machine; and the arm 6 and connecting rods 7 are provided at each end of the rocking shafts 5 .

In the operation, when the folder-blades 95 swing toward the front jaw the stud 9 is brought into contact with the lower end of the eye 12 , and the further movement of the folder means causes depression of the rod and elevation of the guard 2 , until the 100 motion is reversed. Then when rearward movement of the folder-blades occurs, the stud 9 moves up the eye 12 until the guard is allowed to close down by its gravity (or with the aid of a spring, if one is desired,) 105 after which the stud simply swings the end of the rod rearward without exerting any endwise action thereon, until the blades I are again approaching the front jaw.

It is not necessary that in all instances 110 that the shield or guard 2 be made to cover the entire upper surface of the jaw J , provided said guard is of a suitable form and dimension to afford, by its movement, a protection or cautionary warning which will 115 induce an operator or person to remove his hand from a position of danger in respect to the approaching folder-blades I , if perchance it is encroaching on the blade-receiving edge of the jaw.

The guard 2 being operated from the same source of movement that actuates the swinging of the folder-blades, or table-actuating devices, the guard action is rendered accurately synchronous therewith, but just 125 prior to the fold-tucking action where the folder-blade enters beneath the jaw.

What I claim and desire to secure by Letters Patent, is—

1. In a folding machine of the character 130

specified, the combination with the cloth-receiving table, cloth-carrying blades, and front fold-retaining jaw; of an elevatable guard positioned normally adjacent the top 5 surface of said jaw, and means actuated synchronous with the blade movement, for raising said guard therefrom as the cloth-carrying blades approach the jaw, but before inserting the fold of cloth beneath the jaw.

10 2. In combination with the folding blades and fold-receiving-jaw in a cloth-folding machine, a protective guard consisting of an approximately conformed shield or plate adjacently overlying and extending along the 15 top surface of said fold-receiving jaw longitudinally parallel with its edge, an oscillatable support or shaft to which said shield is connected to have movement toward and from the jaw, and operative connections for 20 imparting movement thereto, actuated and controlled by the folder-operating mechanism, and adapted for elevating said shield as the folding blades approach the fold-receiving jaw.

25 3. In combination with the folding mechanism in a cloth-folding machine, including a depressible table, swinging folder-blades, and a stationary jaw; a hingedly attached guard located along the top of the front 30 jaw, and automatically acting means for operating said guard controlled by the movement of the folding mechanism.

40 4. In a cloth-folding machine, including a receiving table, backwardly and forwardly reversing cloth-carrying blades, and fold-retaining jaws beneath which the folds of cloth are delivered by said blades; a protective guard overlying the forward jaw, comprising means for repelling a hand from 45 position of danger as the cloth-carrying blades approach said jaw, movement being imparted thereto from an operating part of the machine.

5. In a cloth-folding machine of the character described, the combination with the 45 table, fold-retaining jaws, folder-blades, and swinging supports therefor; of the operating shaft, cranks fixed on said shaft, rods connecting the cranks and folder-blades, a movable protecting guard arranged upon the 50 front fold-retaining jaw, guard-lifting devices, and connections operatively uniting said guard-lifting devices with the swinging folder-blade supports.

6. In a cloth-folding machine, in combination with the yieldably supported table, backwardly and forwardly swinging cloth-carrying folder-blades, and stationary fold-retaining jaw; of a movable protective guard disposed along the top of said jaw, an axis-shaft parallel with said jaw, means uniting said guard and axis-shaft, and means for 60 rocking said axis-shaft for moving the guard at a predetermined interval, in connection with the means that actuates the 65 cloth-carrier blades.

7. In combination with the fold-forming mechanism, cloth-supporting table, and table-actuating devices, in a cloth-folding machine, and the operating shaft having 70 cams mounted thereon; the pivotally fulcrumed antifriction cam-levers provided with inwardly offset furcated ends having rollers journaled therein, said levers actuated by said cams, connection-rods operatively uniting said levers with the table-actuating devices, fold-retaining jaws co-acting with said table to grip the folds, a repelling protective guard for the forward 75 jaw, and means operating said guard and fold-forming parts in synchronous relation, for the purposes set forth.

Witness my hand this 29th day of August, 1918.

EDWIN H. MARBLE.
